UNITED STATES PATENT OFFICE.

WILLIAM H. NEEDHAM, OF WORCESTER, MASSACHUSETTS, ASSIGNOR TO BOSTON
PRESSED METAL COMPANY, OF WORCESTER, MASSACHUSETTS, A CORPORATION
OF MAINE.

METHOD OF FORMING AN ARTICLE OF SHEET METAL.

1,427,315.

Specification of Letters Patent. Patented Aug. 29, 1922.

Application filed September 10, 1919. Serial No. 322,307.

To all whom it may concern:

Be it known that I, WILLIAM H. NEEDHAM, a citizen of the United States, residing at Worcester, in the county of Worcester and 5 State of Massachusetts, have invented a new and useful Method of Forming an Article of Sheet Metal, of which the following is a specification.

This invention relates to the art of sheet 10 metal working, and particularly to a method of forming articles of a certain type from sheet metal blanks. The articles are of unusual and difficult shape for sheet metal production and a series of unusual and novel 15 operations are involved in the production thereof.

My invention consists in the method of 20 producing sheet metal articles of this general type by the series of operations herein- 25 after described and more particularly pointed out in the appended claims.

The several steps in the production of the finished article are shown in the drawings, together with certain of the tools employed 25 in carrying out the improved method of manufacture.

Figs. 1 to 8 inclusive are side elevations, partly in section, of the article at different stages of its production;

30 Fig. 9 is a side elevation of the finished article, and

Figs. 10, 11 and 12 are sectional views illustrating the tools used in certain steps of the manufacture.

35 The particular article taken for illustration is a ball seat, commonly used in the steering connection of an automobile, the cross section and final appearance of the article being shown in Figs. 8 and 9.

40 In producing this article, I take a round blank of sheet metal and by usual drawing operations transform the blank successively to the cup-like shapes shown in Figs. 1 and 2. Fig. 10 illustrates a pair of drawing

45 dies suitable for these first operations.

The blank shown in Fig. 2 is then preferably squared off at its open end, as indicated in Fig. 3, after which it is subjected to a series of pressing operations by which the 50 cylindrical wall of the open end of the cup is successively reduced in diameter, as shown in Figs. 4, 5, 6 and 7, while at the same time the diameter of the intermediate portion of the cup is maintained substantially constant.

55 The operations illustrated in Figs. 4 to 7 inclusive, are preferably performed with

the article inverted. Fig. 11 shows the cup of Fig. 3 inverted, and placed in the enlarged upper portion 20 of the die 21. The plunger 22 then descends, forcing the blank 60 into the narrow or contracted lower portion 23 of the die, the portion 20 of the die at the same time supporting the narrow lower edges or lips of the plunger 21. A series of dies similar to that shown in Fig. 11 is used 65 to produce the successive reductions indicated in Figs. 4 to 7 inclusive.

The blank is then placed in a die of the general shape indicated at 24 in Fig. 12 and a plunger 25 forces the reduced upper end 70 of the blank against the bottom of the cup, while at the same time, the bottom is forced against the convex surface 26 in the die 24. This operation forces the metal to the position indicated in sectional view in Fig. 8, 75 the finished article having the general outline of Fig. 9.

I thus form from a flat sheet metal blank an article having a strongly reinforced ball seat 30 and a much-reduced cylindrical neck 80 31, together with a flat shoulder 32 against which the article may be firmly seated.

While I have indicated and described my improved method in connection with a single article it will be obvious that other articles of similar outline may be produced by this same method, and accordingly I do not wish to be limited to the details herein disclosed otherwise than as set forth in the 85 claims, but what I claim is:-

90 1. The method of forming an article from sheet metal, which consists in taking a sheet metal blank, drawing the same to the form of an open cup, successively reducing the cylindrical diameter of the cup, adjacent the 95 open end only, and finally forcing the reduced portion axially against the bottom of the cup and simultaneously shaping the latter to form a ball-seat.

95 2. The method of forming an article from 100 sheet metal, which consists in taking a sheet metal blank, drawing the same to the form of an open cup, successively reducing the cylindrical diameter of the cup, adjacent the open end only, and finally forcing the reduced portion axially against the bottom of the cup and shaping the latter to form a 105 ball-seat.

In testimony whereof I have hereunto affixed my signature.

WILLIAM H. NEEDHAM.
